J. H. G. Cook

INVENTOR.

F. SCHRAUDNER,
By Walter Allen.

UNITED STATES PATENT OFFICE.

FREDERICK SCHRAUDNER, OF ST. LOUIS, MISSOURI, ASSIGNOR TO GUS V. BRECHT BUTCHERS' SUPPLY CO., OF ST. LOUIS, MISSOURI, A CORPORATION.

HANGER FOR OVERHEAD RAILWAY-TRACKS.

No. 923,448.

Specification of Letters Patent.

Patented June 1, 1909.

Application filed January 12, 1909. Serial No. 471,901.

To all whom it may concern:

Be it known that I, FREDERICK SCHRAUDNER, a citizen of the United States of America, residing at the city of St. Louis, in the 5 State of Missouri, have invented certain new and useful Improvements in Hangers for Overhead Railway-Tracks, of which the following is a full, clear, and exact description, reference being had to the accompanying 10 drawings, forming part of this specification.

My invention relates to a hanger for use in the support of the rails of overhead railway tracks upon which are operable carriers by which merchandise may be conveyed from 15 point to point in factories, stores, and other places.

The object of my present invention is to provide a hanger of the kind named in which the parts are adjustable relative to each 20 other, thereby permitting of the overhead railway track rails being suspended at various elevations according to different requirements; such, for instance, as that necessitated by differences in the heights of ceilings 25 in buildings from which the track rails are suspended.

Figure I is a side elevation of my overhead railway rail hanger. Fig. II is an enlarged view, partly in side elevation, and partly in 30 vertical section. Fig. III is a rear elevation of the lower end of the hanger. Fig. IV is a horizontal section taken on line IV—IV Fig. I, and looking upward from said line, as indicated by the arrow crossing said line. Fig. 35 V is a horizontal section taken on line V—V Fig. I. Fig. VI is a horizontal section taken on line VI—VI Fig. I.

In the accompanying drawings:—1 designates the suspension rod of my hanger, which 40 is preferably made of uniform diameter from end to end and to which, therefore, the parts that are applied to the suspension rod to be hereinafter enumerated may be readily applied at any point throughout the length of 45 the rod, either in the length in which it is originally made or in any length less than its original length occasioned by cutting off a portion of the rod.

2 designates a head block or top block that 50 is adapted to be secured to a beam or other substantial member in the ceiling of a build-

ing by suitable means, such as a lag screw 5. The block 2 is provided with a sleeve 3, into which the upper end of the suspension rod 1 is fitted to be held therein by set screws 4 55 that are mounted in said sleeve and which are adapted to bear against the suspension rod to connect it to the head block. I preferably employ two of the set screws 4, as seen in Fig. IV, and which are set at angles to each 60 other, but any other desirable number of set screws may be employed.

6 designates the foot block of the hanger to which the overhead railway rail A is secured by any suitable means, such as a bolt B that 65 passes through the rail and the legs 7 of said foot block. The foot block 6 is provided with a bore of approximately the size of the diameter of the suspension rod 1 and in the foot block are set screws 8, preferably ar- 70 ranged in a manner corresponding to the arrangement of the set screws 4 in the head block 2, as seen in Fig. VI.

9 designates a brace that is adapted to be secured by suitable means to a member of the 75 ceiling in a building near the head block 2 of the hanger and which extends downwardly and to the suspension rod 1 near its lower end.

10 is a binding collar fitted to the suspen- 80 sion rod 1 and provided with an extension containing a pocket 11 adapted to receive the lower end of the brace 9. In the extension of said collar is a set screw 12 that is adapted to impinge against the brace 9 and hold said 85 brace clamped between the screw and the suspension rod, as illustrated in Figs. II and V.

I claim:—

A hanger of the character described com- 90 prising a hanger block formed with a sleeve, a suspension rod supported in the sleeve, a foot block for carrying a rail adjustably secured to the suspension rod, a brace, a bind- 95 ing collar, through which the suspension rod is inserted, formed with a pocket for the brace and adjustably secured upon the latter.

FRED. SCHRAUDNER.

In the presence of—

H. G. COOK,
E. B. LINN.
